US00D653398S

(12) United States Design Patent
Acierto et al.

(10) Patent No.: US D653,398 S
(b5) Date of Patent: * Jan. 31, 2012

(54) PERSONAL CARE PACKAGE

(75) Inventors: Gwen Sheila Trinidad Acierto, Owings Mills, MD (US); Mark Jay Barnes, Lebanon, OH (US); Christopher Louis Hansen, Loveland, OH (US); Folke Schlueter, Geneva (CH); Ian Andrew Carnduff, New York, NY (US)

(73) Assignee: The Procter & Gamble Company, Cincinnati, OH (US)

() Term: 14 Years

(21) Appl. No.: 29/387,303

(22) Filed: Mar. 11, 2011

Related U.S. Application Data

(62) Division of application No. 29/360,818, filed on Apr. 30, 2010, now Pat. No. Des. 636,940.

(51) LOC (9) Cl. 28-03

(52) U.S. Cl. D28/84; D28/88

(58) Field of Classification Search D28/73, D28/76, 79, 85-90, 84; 206/581, 823, 385; 401/68, 72, 88, 17, 126-130; 132/317, 318, 132/320, 218; D9/503-504

See application file for complete search history.

(57) CLAIM

The ornamental design for a personal care package, as shown and described.

DESCRIPTION

FIG. 1 is a perspective front view of a personal care package, embodying the new design;

FIG. 2 is a front view of the design shown in FIG. 1; the back, right side, and left side views of the design shown in FIG. 1 are the same;

FIG. 3 is a top view of the design shown in FIG. 1; and, FIG. 4 is a bottom view of the design shown in FIG. 1. The broken lines in the drawings are for illustrative purposes only and form no part of the claimed design. The diagonal line shading represents transparency.
